CLAIM

The ornamental design for battery for wearable physiological monitor, as shown and described.

DESCRIPTION

FIG. 1 is a top perspective view of a design for a battery for wearable physiological monitor;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top-front perspective view thereof, engaged with a wearable physiological monitor and strap;

FIG. 9 is a top-rear perspective view thereof;

FIG. 10 is a top-front perspective view thereof, partially engaged with a wearable physiological monitor and strap;

FIG. 11 is a bottom-rear perspective view thereof; and,

FIG. 12 is a top perspective view thereof, engaged with a wearable physiological monitor and strap on a user's wrist. The broken line showing of the physiological monitor, strap, and user's wrist illustrate environmental structure and form no part of the claimed design. All other broken lines illus-
